COMBINATION LUGGAGE CARRIER AND FOLDING BOAT

Charles L. Rough, 3511 Burritt Way, La Crescenta, Calif.

Filed Oct. 4, 1960, Ser. No. 62,375

Term of patent 14 years

(Cl. D71—1)

FIG. 1.

FIG. 2.

FIG. 6

FIG. 3.

FIG. 4.

FIG. 5.

FIGURE 1 is a perspective view of a combination luggage carrier and folding boat, showing my new design;

FIGURE 2 is a top plan view thereof;

FIGURE 3 is a side elevational view thereof, the opposite side being substantially the same in appearance;

FIGURE 4 is a rear elevational view thereof;

FIGURE 5 is a bottom plan view thereof; and

FIGURE 6 is a sectional view taken along line 6—6 on FIGURE 1 and showing the shape of the surface on an enlarged scale.

The dominant features of my design reside in the portions shown in full lines, the trailer and boat fittings shown in dot and dash lines in FIGURES 1, 2, and 3 being for illustrative purposes only.

I claim:

The ornamental design for a combination luggage carrier and folding boat, as shown and described.
